UNITED STATES PATENT OFFICE.

JOSEPH A. STEINMETZ, OF PHILADELPHIA, PENNSYLVANIA.

SNOW DISPOSAL.

1,418,337.

Specification of Letters Patent. Patented June 6, 1922.

Application filed April 12, 1921. Serial No. 460,832.

To all whom it may concern:

Be it known that I, JOSEPH A. STEINMETZ, a citizen of the United States, and resident of Philadelphia, in the county of Philadelphia and State of Pennsylvania, have invented certain new and useful Improvements in Snow Disposal, of which the following is a specification, reference being had therein to the accompanying drawing.

10 My invention relates to the disposal of snow in streets by temporarily storing it on a part of the area where it falls and subsequently removing it, either before or after the snow-fall ceases.

15 It is said that the snow blockade of 1919-1920 cost the city of New York some sixty millions of dollars, no available means of removal proving adequate, and slush freezing in conduits and making the running 20 of cars impossible even after all surface ice had been laboriously removed, days after the storm ceased.

25 I select those portions of the sidewalks and pavements which are most indispensable to traffic, and move the snow laterally from those parts to portions not so essential, allowing no great accumulation of snow on the portions to be kept fairly clear for use, removing snow from the storage areas as soon 30 or as rapidly as available facilities will permit. By this means, the pavement and sidewalk are virtually narrowed, but are otherwise readily kept in condition for use, snow never being thrown back and forth to and 35 from the car tracks, for example, as most towns having only ordinary methods meet the situation, allowing the street cleaning force and the street railway management to fight the matter out in thus repeatedly handling the same snow.

40 In the accompanying drawings, which are diagrammatic,

Fig. 1 is a cross-section of a street with my invention in use.

45 Fig. 2 is a similar section, snow being indicated.

Fig. 3 is an analogous section showing a slight modification.

50 Fig. 4 is a section showing a different form of snow-retaining stringer.

Fig. 5 is a like section showing parallel stringers tied together and arranged for at will increasing their height.

Fig. 6 is a perspective view of a tie bar

used in increasing the height of the stringers.

Fig. 7 is a similar view of a tie bar used for detachably connecting the stringers at the street surface.

Fig. 8 is a sectional view showing a simple stringer connected to the curb by a flat tie lying on the sidewalk.

In these figures, A represents the surface of a street provided with street railway tracks B, B, one of the sidewalks normally extending from the usual curb D to the building line E. Stringers F are laid, parallel to the curbs, along all the streets in the area to which the invention is to be applied, so that every street will have on each side a strip laterally bounded by these stringers, and snow falling on other portions of the street and sidewalk is piled upon this strip, so that with a moderate force of men any great accumulation of snow on the sidewalk or street may be prevented, the stored snow being removed by other men meantime, or by the same men after the snow ceases to fall.

The stringers employed may be of wood such as "scantling," or may be downwardly open V-shaped structures of metal or wood, as shown at F', Fig. 3, or may be metal L bars F'', shown in Fig. 4.

The second form shown has the advantage of allowing melted snow or rain to flow down inclined street surfaces and ultimately pass into the sewers. One of these stringers may, if desired, be placed in each gutter as shown in Fig. 2 to prevent accumulation of water when conditions are such that snow melts rapidly, thus avoiding the necessity of shoveling the snow to form an open channel in the gutter.

In some cases, I lay down metal bars G, shown in Fig. 7, to receive stringers F''', Fig. 5, and should the accumulation of snow continue so long as to make it desirable, these stringers can be increased in height by placing upon their upper edges metal tie-bars I having upwardly and downwardly turned retaining projections I', I'' to engage both the lower stringer and the additional superposed stringer J. Of course this extension in height may be repeated, each added set of stringers being tied by a set of crossbars.

Fig. 8 a single stringer F'' is shown as

held parallel to and at a suitable distance from, the curb D by a thin, flat bar G' bent up at one end and down at the other and secured to the stringer and, if desired, to the 5 curb by a screw or the like.

It is also plain that I am not limited to a single stringer nor to a single pair of stringers, nor to one stringer on the sidewalk and one on the street roadway, and it 10 is equally clear that the length of the tie bars may be varied according to the conditions in any given case, as when streets and sidewalks vary in width.

No attempt has been made to show all 15 forms and arrangements that may be desirable, for the system being in mind, any person having good judgment will readily select an arrangement which suits his especial conditions.

20 20. What I claim is:

1. For aiding snow disposal in streets having gutters and curbs, the combination with a readily removable snow-retaining stringer parallel to and everywhere at a selected distance from the curbs, of thin bars resting on 25

the same surface as the stringer and holding the latter in place upon said surface.

2. The method of disposing of snow falling in a city street which consists in providing readily removable snow retaining devices bounding a relatively narrow area extending longitudinally with reference to the street, removing to such area snow falling alongside the same, and at a later time mechanically removing the snow from that 30 35 area.

3. For temporarily storing snow falling in city streets, the combination with stringers laterally bounding the less used strips of the street area, of ties detachably connecting the stringers, and means for at will increasing the vertical height of the stringers. 40

4. For laterally retaining snow on predetermined strips of a street surface, hollow, downwardly open stringers laterally bounding said strips. 45

In testimony whereof I hereunto affix my signature.

JOSEPH A. STEINMETZ.
